UNITED STATES PATENT OFFICE.

HARRY F. HAMPSHIRE AND FRANK B. CRANMER, OF PHILADELPHIA, PENNSYLVANIA, ASSIGNORS TO THOMSON PRINTING COMPANY, A CORPORATION OF NEW JERSEY.

DELIVERY ATTACHMENT FOR PRINTING-PRESSES.

1,399,477.

Specification of Letters Patent.

Patented Dec. 6, 1921.

Application filed December 24, 1920. Serial No. 433,014.

To all whom it may concern:

Be it known that we, HARRY F. HAMPSHIRE and FRANK B. CRANMER, citizens of the United States, both residing at Philadelphia, in the county of Philadelphia and State of Pennsylvania, have invented certain new and useful Improvements in Delivery Attachments for Printing-Presses, of which the following is a specification.

10 The object of this invention is to provide an improved delivery mechanism, particularly adapted for use in conjunction with printing presses, and designed for the purpose of conveying sheets from such a press 15 so that they will fall and pile upon one another with the side of each that has just been printed facing either downwardly or upwardly.

Frequently it is necessary to print sheets 20 of paper, or the like, with progressive numbering, in which case it is desirable to deliver the said sheets from the press in a given order, generally with their faces down, so that when the pile is inverted the lowest 25 number appears upon the top sheet from which successive numbers increase in value downwardly, thus making it possible to assemble the numbered sheets with others in the desired order, or to feed the said sheets 30 again into the press for a subsequent impression upon the reverse side, which latter may also comprise numbers in numerical progression, and which it is obvious would generally be desirable to run in the same order as those used in the first impression 35 upon the obverse side.

Then again a job may be put upon the press which requires that the printed sheets be delivered in the usual way, namely, with 40 their faces up and progressing from the lower to the upper part of the pile. This invention, therefore, provides an arrangement whereby with but a slight alteration the sheets are taken as they are delivered 45 from the press, and are stacked with either face up as may be desired.

And a further object is to provide a set 50 of suitable racks for removably supporting a series of rolls, over which conveyer-belts pass to carry a printed sheet from the press, either directly to a tray in which the sheets are deposited face up and with ascending numbering upon them also progressing up-

wardly, or toward a second belt passing between and around a second set of rolls and 55 operative to turn the sheets face downward as they are delivered into a tray and with their numbers progressing upwardly through the pile.

With these and other objects in view, the present invention comprises further novel details of construction and operation hereinafter fully brought out when read in conjunction with the accompanying drawings, in which Figure 1 is an elevation of one 60 side of the preferred embodiment of this invention in operative association with any suitable standard type of printing-press; Fig. 2 is a elevation of the opposite side of 65 the same; Fig. 3 is a top plan view of the 70 improved delivery device together with that portion of a printing-press which propels the printed sheets from the latter toward and upon the former; Fig. 4 is a vertical section on the line 4—4 of Fig. 3; Fig. 5 is 75 a similar section on the line 5—5 of Fig. 3; and Fig. 6 is a central vertical longitudinal section of the apparatus shown in Fig. 3.

Referring to Figs. 1 and 2, there is illustrated any standard type of a so-called job 80 printing-press, comprising a table 1, upon which is placed a stack of paper, cards, or the like, 2, which are to be printed, and from which pile the individual sheets are removed successively by any well-known means, either 85 automatic or manually operated, until they in turn rest against the forward face of the platen 3, and while against the said platen the sheets receive an impression from type, cuts, or the like, removably secured within 90 the chase-supporting members 4 over which the inking-rolls 5 pass to convey ink to the said type from the ink turn-table 6, supplied in turn from any suitable ink-reservoir and feed-mechanism 7.

The printing-press is designed to be run in any suitable manner as by an electric-motor (not shown), the same having its speed regulated by any desired form of rheostat or resistance box 8, while a driving-belt 9 or other power-transmitting means extends from the said motor and rotates a pulley 10 upon one side of the press. The said belt-pulley rotates a fly-wheel 11 and is also secured to a shaft, and thereby also rotates 105 a pinion 12 which meshes with and rotates

a relatively large gear 13, to the outer surface of which is pivotally connected a pitman 14, having its opposite free end secured to the frame-work 15 which supports the 5 type in the turn-table, the ink-reservoir, and inking-rolls, to oscillate said last-named members as a unit toward and away from the platen 3 about a pivotal support 16 at the lower portion of the metal foundation- 10 frame 17 of the press.

The gear 13 also operates the paper-feeding mechanism 18 through a series of gears 19, and furthermore rotates a gear 20, which latter is keyed upon the same shaft and rotates a pinion 21 meshing with and operative to rotate a relatively larger gear 22 carried by a shaft adjacent to and extending between the lower portions of the said frame 17. This last-named gear 22 is pivotally connected with a pitman 23, which extends toward and is pivotally connected at its outer end portion to a lever 24 which operates an oscillatory arm 25, provided in turn at its outer free end with paper-gripping jaws 26, the lower of which is adapted to be operated by a suitably actuated member 27 to grip the lower edge portion of a sheet 28 immediately after said sheet has received an impression of the type and the 30 type-supporting frame 4.

By reason of the rotary motion of the gear 22, the jaws 26 oscillate throughout an arc and remove the printed sheet from the platen 3 to the position shown in Figs. 1 35 and 2, where spaced fingers 29, between which the said jaws pass, remove the forward edge portion of the sheet from the latter and permit it to drop by gravity directly upon a conveyer-belt 30, which 40 comprises a portion of the improved delivery-mechanism.

The said conveyer-belt is rotatably mounted beneath the press upon a roller 31, and extends from beneath said press between 45 spaced upright members 32, which at their upper end support the fingers 29, and which also removably support a shaft 33 carrying a series of wheels 33^a, which press downwardly upon the upper portion of the 50 said conveyer-belt and serve both to prevent vibration of the said belt and also to press air from beneath the sheets 28 after they have fallen thereupon, said sheets being led beneath said wheels by means of a 55 suitable partition 34 suspended from a member 35 connecting the upper portions of the members 32, and said partition extending downwardly to within a short distance of the said conveyer-belt.

60 At its opposite end the said belt passes over a roll 36, which is removably supported at its ends upon spaced frame-members 37 by means of a shaft which also carries a pulley 38 connected by a suitable belt 39 to a pulley 40 keyed to a shaft 41,

which in turn is driven by means of a belt 42 from a pulley 43 carried by a shaft which also supports a pulley 44, rotated by means of a belt 45 passing also over a pulley 46 keyed to the same shaft with the gear- 70 wheel 22 of the printing-press.

When the improved delivery-mechanism is arranged as shown in Fig. 6, the printed sheet 28 passes from the conveyer-belt 30 over a roll 47 and into a receptacle 48, 75 where it may lie either flat as shown in the drawings upon a plate 49 or may be delivered so that the successive sheets slide toward and are held in alinement by direct contact with a member 50 unitarily secured 80 to the said plate, and, if desired, also pivotally mounted at 51 to oscillate into any desired position as may be determined by a pin or other member inserted through the spaced apertures 52 or the like in the laterally opposite sides of the receptacle 48.

The spaced frame-members 37 removably and revolvably support at their uppermost portions a roller 53 carried by a shaft 54, to which is also keyed a pulley 55 connected 90 by means of a belt 56 and for the purpose of revolving the roller 47. Also secured to said last-named shaft is a pulley 56^a, which is connected by means of a belt 57 to a pulley 58 carried by the shaft 41. The 95 members 37 adjacent to their lowermost portions revolvably and removably support a shaft 59 carrying a roll 60, over which extends a conveyer-belt 61, which latter also extends over the roller 53 and is driven 100 thereby, while said last-named conveyer-belt likewise engages the belt 30 as they together pass around the roll 36 throughout a portion of its circumference, the said belt 61 being driven by the roller 53 and in turn 105 rotating the roll 60.

That lower portion of each of the frame-members 37 which is nearest to the members 32 is provided with means for removably and rotatably supporting a shaft 62, 110 carrying between said frame-members a series of wheels 63, and also a pulley 64 which is driven by means of a belt 65 from a pulley 66 also carried by the shaft 41. This said last-named shaft furthermore 115 carries a pulley 67 which is connected by means of a belt 68 to a pulley 69 carried by the shaft 54.

When the device is arranged as shown in Figs. 1, 2, 3 and 4, the printed sheets 120 28 are carried by means of the conveyer-belt 30 toward the roll 36, and are then engaged by the belt 61 and carried downwardly partially around the said roll 36, and removed from said last-named belt by 125 means of a suitable substantially horizontally extending plate 70, through apertures in which extend the wheels 63, which wheels in turn catch the sheet and propel it toward and into a suitable tray formed by a 130

bottom wall 71 and terminating downwardly in an upwardly extending wall 72, against which the successive sheets slide and are piled one upon another in vertical alignment.

In the operation of the improved delivery mechanism when arranged with the conveyer-belt 61 present and the sheets delivered into the tray 71-72, it will be noted that the face of each sheet which has received the ink impression and has lain face upwardly upon the conveyer-belt 30 is finally delivered into the said tray with its face downwardly. Thus it will be obvious that, if the printing-press is provided with a numbering device for printing upon the successive sheets correspondingly progressing numbers and are delivered face downward upon the pile, the said pile as a whole may be removed at any desired intervals and inverted so that in inverted position the numbers of the sheets comprising the pile progress downwardly, while in the arrangement of the mechanism as shown in Fig. 6 and previously described the sheets are delivered face-up within the receptacle 48, and with their numbers progressing from the bottom toward the top of the resulting pile.

Having thus described our invention what we claim and desire to protect by Letters Patent of the United States is:—

1. A delivery mechanism, comprising a conveyer belt extending over a roll and adapted to receive a sheet, to convey the sheet toward said roll, and to discharge the sheet therefrom in a given position in a receptacle, and a demountable belt adapted to extend partially around said roll and operative when present to maintain the sheet upon said first belt for a longer period to prevent its delivery in said given position, and operative to cause the delivery of the sheet in an inverted position in a second receptacle.

2. A delivery mechanism, comprising a conveyer-belt extending between two rolls and operative to convey sheets of paper from a printing-press toward the second of said rolls, a frame operative to support said second roll, third and fourth rolls also supported by said frame upon substantially opposite sides of said second roll, a belt extending over and between said third and fourth rolls and movable in fixed relation with said first belt over said second roll, said second belt being operative to maintain a sheet upon said first belt until the sheet is substantially inverted beneath said first roll, a roll adjacent to the lower portion of said second belt, means operative to lead the sheet from said second belt and toward said last-named roll, and a tray adapted to receive sheets from said last-named roll.

3. A delivery mechanism, comprising a

conveyer-belt extending between a first and a second roll and adapted to receive a printed sheet from a printing-press, and to convey the sheet toward the second roll, a receptacle adapted to receive the sheet from said belt after passing said second roll, and a belt extending between two rolls respectively above and below said second roll, a second receptacle beneath said first belt, and said second belt being operative to maintain the sheet upon said first belt to prevent the sheet entering said first receptacle and to direct it instead toward said second receptacle.

4. A delivery mechanism, comprising a conveyer-belt extending between a first and a second roll and adapted to receive a printed sheet from a printing-press, and to convey the sheet toward the second roll, a frame removably supporting said second roll, a receptacle adapted to receive the sheet from said belt after passing said second roll, and a second belt extending between two rolls respectively above and below said second roll and removably supported by said frame, a second receptacle beneath said first belt, and said second belt being operative to maintain the sheet upon said first belt to prevent its entering said first receptacle and to direct it beneath said first belt, a member operative to direct the sheet from said second belt, and a roll operative to convey the sheet from said member toward said second receptacle.

5. A delivery mechanism, comprising a conveyer belt extending over a roll and adapted to receive a sheet, and to convey the sheet to said roll, a receptacle adapted to receive the sheet from said belt after passing said roll, and a removable belt adapted to extend between two rolls respectively above and below said first roll, a second receptacle, and said second belt being operative when present to maintain the sheet upon said first belt to a point where the sheet is prevented from discharging into said first receptacle and is directed instead in an inverted position into said second receptacle.

6. A delivery mechanism, comprising a conveyer belt extending between a first and a second roll, and adapted to receive a sheet from a printing press, and to convey the sheet toward said second roll, a frame to support said second roll, a receptacle adapted to receive the sheet from the said belt after passing said second roll, and a second belt extending between two rolls and partially encircling said second roll, said frame also removably supporting said last-named two rolls, a second receptacle; and said second belt being operative to maintain said sheet upon said first belt to prevent its entering said first receptacle and to direct it toward said second receptacle.

7. A delivery mechanism, comprising a conveyer belt extending over a roll and adapted to receive a sheet, and to convey

the sheet to said roll, a receptacle adapted to receive the sheet from said belt after passing said roll, and a removable means adapted to extend above and below said roll, a 5 second receptacle, and said means being operative when present to maintain the sheet upon said belt to a point where the sheet is

prevented from discharging into said first receptacle and is directed instead in an inverted position into said second receptacle. 10

In testimony whereof we have affixed our signatures.

HARRY F. HAMPSHIRE
FRANK B. CRANMER
